UNITED STATES PATENT OFFICE.

GEORGE A. BURNHAM, OF SAUGUS, MASSACHUSETTS, ASSIGNOR, BY MESNE ASSIGNMENTS, TO CONDIT ELECTRICAL MANUFACTURING COMPANY, A CORPORATION OF MASSACHUSETTS.

ELECTRIC SWITCH.

Application filed January 29, 1920. Serial No. 354,920.

To all whom it may concern:

Be it known that I, GEORGE A. BURNHAM, a citizen of the United States, residing at Saugus, in the county of Essex and State of

5 Massachusetts, have invented an Improvement in Electric Switches, of which the following is a specification.

My present invention relates to oil immersed electric switches of relatively high 10 current carrying capacity.

In another application, Serial No. 309,853, filed July 10, 1919, I have shown a switch of such type having means by which to reduce the gaseous pressure within the 15 switch and to absorb energy developed upon circuit interruption, comprising a resiliently supported oil receptacle adapted to be moved downward upon the development of an abnormal gas pressure within the switch.

20 As an object of my present invention, I provide means whereby the oil contained in the switch is adapted to move or yield upon the development of an abnormal gaseous pressure within the switch, whereby to increase the expansion space of the switch and 25 to absorb energy upon circuit interruption.

To accomplish this result I provide the switch with a double oil receptacle, one receptacle within the other, and in free oil 30 communication at their lower ends. The inner receptacle is adapted to contain the switch members and the outer receptacle has a closed top whereby to retain air or other gases which serve as an elastic cushion 35 against which the oil is forced upon the development of gaseous pressure during circuit interruption and by which energy is absorbed. I may also removably depend the double oil receptacle yieldingly from the 40 fixed frame, as illustrated in the above specification.

A further object of my invention is to provide the device as an attachment for electric switches.

45 A yet further object is to improve the construction and operation of an electric switch.

Fig. 1 is a side elevation, partly in sec-

tion, of an electric switch embodying my invention.

Fig. 2 is a sectional plan view along line 50 2-2 of Fig. 1.

Fig. 3 is a vertical section along line 3-3 of Fig. 1.

Fig. 4 is a vertical section of a modified 55 form of double oil receptacle.

Fig. 5 is a side elevation, partly broken away, of the oil receptacle of Fig. 4.

Fig. 6 is a detail of a modified form of 60 wall strengthening means.

As here shown, the oil switch with which my invention is associated includes the fixed switch-supporting frame having the arm 11 by which the switch is secured to a support and bearing the stationary switch-members 65 12, the movable switch member 13 and switch-operating mechanism 14. Said switch frame is formed with the peripheral depending flange or apron 15 adapted to surround and be closely spaced from the top 70 of the oil receptacle thereby to provide a vent space 15^a for the switch.

The oil receptacle of the switch comprises the inner receptacle 16 forming an inner 75 compartment and the outer receptacle 17 containing and peripherally spaced from the inner receptacle and forming an outer compartment. In Fig. 1, the inner oil receptacle is shown as having an open bottom terminating above the bottom of the outer oil 80 receptacle whereby to provide a passage of ample dimensions for the relatively unrestricted flow of oil between the two receptacles. In Fig. 4 the inner oil receptacle is illustrated as closed by the bottom 18, and a 85 plurality of perforations or apertures 18^a are formed in the side walls of the inner receptacle, close to the bottom thereof, whereby to provide for free oil communication between the receptacles. 90

The side walls of the inner receptacle extend above the top of the outer receptacle and are received within the apron 15 of the switch frame which comprises a cover for the oil receptacle. The top of the outer oil 95 receptacle is closed by reflexing the top of

its side walls into contact with the side walls of the inner receptacle and sealing the connection as by welding, in such a manner as to form a practically air tight joint. By 5 this construction a closed space or chamber 19 is formed between the two receptacles and at the top of the outer receptacle in which air or other gases are entrapped, when the receptacles are filled with oil to 10 the designed level; and the oil receptacle thus formed has the reduced top-portion and the enlarged body-portion extending beyond and depending below the flange and the switch frame. The switch frame and 15 oil receptacle comprise a casing supporting and containing the switch members or contacts.

The double oil receptacle rests upon the supporting grid 20 to which it may be secured by the bolts 21 extended through lugs 22 of the outer receptacle and threaded into the grid. Supporting rods 23 are secured to said grid and extend thereabove into the recesses 24 of lugs 25 of the switch frame 10. 20 Springs 26 are received in said recesses about said rods and nuts 27 removably and adjustably received on the ends of said rods engage said springs, by which construction the oil receptacle is removably secured yieldingly to the switch frame, and the tension of 25 the springs may be adjusted, whereby to yield under predetermined gaseous pressure conditions within the switch. The means whereby the double oil receptacle is supported yieldingly from the switch frame may be omitted if desired without detracting 30 from the value of my invention but I find it of value when associated therewith.

Said springs 26 are adapted to retain the 40 oil receptacle in substantial contact with the under side of the switch frame and the top of the receptacle are sufficient to provide a proper gas vent over the top of the receptacle into 45 the vent space between the apron 15 and down over the side walls of the receptacle into the atmosphere. However stop-members 28 fixed to said supporting rods 23 may be arranged to engage said lugs 25 thereby to 50 govern the height of the gas vent over the top of the oil receptacle.

Reinforcing means are arranged between the side walls of the two receptacles whereby to support the side walls of the inner receptacle against lateral pressure, and strengthen the oil receptacle as an entirety. In Figs. 1, 2 and 3 the reinforcing means comprises a plurality of cups 29 fixed by welding or otherwise at spaced intervals to the inner side of the walls of the outer receptacle and extended in proximity to the inner receptacle. In Figs. 4, 5 and 6 the supporting means comprises the channel members 30 secured by the side walls thereof 60 to the inner face of the outer receptacle;

and the walls of the channel-members may be provided with slots or openings 31 therethrough whereby to admit of the flow of oil through the space between the two receptacles. Said channel members are continuous, 70 and provide considerable resistance to lateral distortion of the side walls.

The oil receptacle is adapted to be filled with oil to some suitable level *a—a*, Fig. 1, over the stationary and movable switch 75 members, and the oil will enter the space between the oil receptacles and be at the same level on both receptacles; and the top of the chamber 19 will contain air or other gases. A pet cock 32 arranged in the top of 80 the outer oil receptacle is in communication with said space 19 whereby to provide a vent for said chamber when the receptacle is filled with oil and is then adapted to be closed so that the compression space is substantially 85 air tight. The oil level in the receptacle is adapted to be such that a substantial gas expansion space 33 is provided between the top of the oil in the inner oil receptacle and the switch frame. 90

Upon the interruption of a circuit carrying current, the heat of the resulting arc will cause the generation of gas within the inner oil receptacle and the pressure therein will sharply rise. The increase of pressure 95 causes an unbalancing of pressure on the oil in the inner and outer receptacles and causes a flow of oil downwardly from the inner receptacle and upwardly into the space between the two receptacles and the compression of and storage of energy in the entrapped air in the chamber 19, thereby increasing the volume of the expansion space 100 above the surface of the oil in the inner receptacle and reducing the gaseous pressure therein and preventing shock to both receptacles. By the yielding suspension of the double oil receptacle the device as an entirety may yield and thereby additionally absorb the shock. Upon the eventual relief 110 of the generated gases over the top of the oil receptacle the oil will return to its normal position by the expansion of the compressed entrapped air or gases, which will forcibly 115 return the oil, and the switch will be in readiness to interrupt the circuit again.

I claim:

1. An oil receptacle for electric switches comprising a unitary structure having outer and inner walls peripherally spaced from each other arranged to form a closed top outer chamber and an open top inner chamber in communication below the oil level in the receptacle and means removably to secure the receptacle yieldingly to an electric switch. 120

2. An oil receptacle for electric switches comprising a unitary structure having outer and inner walls peripherally spaced from each other arranged to form a closed top 125 chamber in communication below the oil level in the receptacle and means removably to secure the receptacle yieldingly to an electric switch. 130

outer chamber and an open top inner chamber in communication below the oil level in the receptacle and a manually controlled valve arranged at the top of the outer chamber.

3. An oil receptacle for electric switches having inner and outer peripherally spaced walls, said inner wall extended above the outer wall, and the top portion of said outer

wall reflexed and secured to said inner wall 10 thereby to form a closed chamber between the walls in open communication below the oil level in the receptacle with the space between the inner walls.

In testimony whereof, I have signed my 16 name to this specification.

GEORGE A. BURNHAM.
